(57) **CLAIM**

The ornamental design for an extendable dish rack, as shown and described.

DESCRIPTION

FIG. 1 is a front, top, right side perspective view of an extendable dish rack showing the claimed design;

FIG. 2 is a rear, bottom, left side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a perspective view of the extendable dish rack in an extended condition with dishes stored.

The broken lines shown in the drawings represent portions of the extendable dish rack that form no part of the claimed design.
